CLAIM

The ornamental design for a portable stand, as shown and described.

DESCRIPTION

FIG. 1 is a front, right and top perspective view of a portable stand showing my new design;
FIG. 2 is a rear, left and bottom perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a top view thereof;
FIG. 8 is a bottom view thereof;
FIG. 9 is a perspective view of the portable stand in an alternate configuration;
FIG. 10 is a perspective view of the portable stand in another configuration;
FIG. 11 is another front, right and top perspective view of the portable stand in another alternate configuration; and,
FIG. 12 is another rear, left and bottom perspective view thereof.
